UNITED STATES PATENT OFFICE.

GEORGE R. WILLIAMS, OF BROOKLYN, NEW YORK, ASSIGNOR, BY MESNE ASSIGNMENTS, TO E. C. FULLER COMPANY, OF NEW YORK, N. Y.

SLANT-BOARD FOR PRINTING-PRESSES, &c.

SPECIFICATION forming part of Letters Patent No. 738,967, dated September 15, 1903.

Application filed June 25, 1902. Serial No. 113,119. (No model.)

To all whom it may concern:

Be it known that I, GEORGE R. WILLIAMS, a citizen of the United States, and a resident of Brooklyn, in the county of Kings and State of New York, have invented a new and useful Improvement in Slant-Boards for Printing-Presses, &c., of which the following is a specification.

This invention relates to the slant-boards which are arranged upon the main feed-boards of printing-presses, paper-feeding and other machines at the delivery end of the main feed-board, and particularly to that kind of slant-boards which are composed of a transverse series of metallic fingers or blades, each arranged lengthwise of the feed-board. These fingers have been secured at their upper ends to a transverse bar or rail by detachable fastenings, such as screws.

The objects of this invention are to provide simple means for attaching the fingers to the supporting bar or rail, which means enables the fingers to be readily attached or detached and to be adjusted laterally on the bar or rail, as the width of the sheets or other conditions may require or render desirable, also to improve the attaching devices in other respects.

In the accompanying drawings, Figure 1 is a fragmentary top plan view of my improved slant-board. Fig. 2 is a fragmentary top plan view of one end of the slant-board on an enlarged scale. Fig. 3 is a longitudinal section through one of the intermediate fingers of the slant-board in line 33, Fig. 2. Fig. 4 is a perspective view of one of the intermediate fingers. Fig. 5 is a fragmentary perspective view of the supporting bar or rail. Fig. 6 is a sectional side elevation of one of the end fingers, the section being taken in line 66, Fig. 2. Fig. 7 is a cross-section of one of the end fingers in line 77, Fig. 2. Fig. 8 is a perspective view of one of the end fingers.

Like letters of reference refer to like parts in the several figures.

A represents the main feed-board of a printing-press, paper-feeding machine, or other machine.

B represents a transverse supporting bar or rail arranged above the feed-board near

the delivery end thereof, and B' represents a similar bar arranged parallel to the bar B in rear of the latter. The bar B' is somewhat lower than the bar B and the two bars form together the transverse channel in which the side-registering mechanism (not shown) is arranged. The bars B B' are secured at each end to a supporting-bracket b, carried by the feed-board. The front supporting-bar B is provided on its rear side, the side which is turned toward the delivery end of the feed-board, with a transverse guide C, which is preferably formed separately from the supporting-bar and secured thereto by riveting or otherwise. The guide C is provided on its face with an upper horizontal rib c, having a horizontal top c', which is arranged slightly below the top of the supporting-bar, and with an overhanging or dovetail lower side c'', forming the top of a dovetail groove c''' below which the guide C is provided with a horizontal rib c'', having horizontal upper and lower sides. The supporting-bars B B' preferably have the form of angle-bars, as shown.

D represents the fingers, which are preferably formed each of a narrow steel plate and provided at the base or attaching end with a clip or shoe E, by which the finger is attached to the supporting-bar. This clip and the guide C of the supporting-bar are so shaped and constructed that the clip can be engaged with the guide and moved along the same to the position which the finger is desired to occupy. To this end the face of the clip is provided with an upper horizontal rib e, having horizontal top and bottom sides, a groove e' below said rib, and a lower rib e'', which has a dovetail upper face and is divided at or near its middle into two parts or lugs by a notch or space f, while the upper rib c of the guide C is provided at one or more points of its length with a pair of notches f' of the proper length to permit the ribs or lugs e'' of the clip to be passed downwardly through these notches. Upon placing the finger with its clip upon the guide, with the ribs or lugs e'' of the finger standing above the notches f' of the guide, the clip can be pushed down until the dovetail ribs e'' of the clip stand in line with

the dovetail groove c^3 of the guide. The finger can now be moved along the guide, whereby the lugs of the finger are moved away from the notches of the guide and the finger becomes securely attached to the guide and supporting-bar. The finger can be readily shifted along the bar to the desired position and can be readily removed from the bar upon placing its lugs in line with the notches of the guide and moving the clip upwardly. The clips are preferably made of cast metal and secured to the fingers by riveting.

g is a plate-spring which extends rearwardly from the clip below the finger and which is secured at one end to the clip by riveting or otherwise and bears with its other free end upon the rear bar B' . This spring is of such shape that it is strained by attaching the finger to the supporting-bar and this tension of the spring holds the finger snugly in place and prevents rattling. The spring, however, permits the finger to be readily raised out of engagement with the guide.

Each end finger D' is preferably made somewhat wider than the intermediate fingers D in order to provide a wide support for the edge of the sheet and is provided at its outer side with a short auxiliary or stub finger D^2 . The latter does not extend to the supporting-bar in order to leave free space above this stub-finger for parts of the side-registering mechanism, but is supported from the end finger D' by a transverse bar g' , which is preferably somewhat depressed below the level of these fingers.

My improved attaching means permits each finger to be easily attached to or removed from the supporting-bar and to be adjusted laterally on the bar to the desired position. In changing from one size or kind of sheets to another it is sometimes necessary or desirable to arrange the fingers more closely together and to increase the number of fingers correspondingly or to spread the fingers farther apart and to remove some of the fingers. My invention provides means for doing this conveniently and quickly. The attaching means is also very convenient, because the fingers and their supporting parts contain the attaching means, and separate fastening devices, such as screws, are dispensed with.

I claim as my invention—

1. In a slant-board, the combination of a support and independent laterally-adjustable fingers arranged side by side, the support being provided on its upright rear side and the fingers on their upright front faces with interlocking transverse projections and grooves by which the fingers are adjustably attached to the support, substantially as set forth.

2. In a slant-board, the combination of a transverse support and independent laterally-adjustable fingers, arranged side by side with their upper surfaces flush with the upper sur-

face of said support, the support and fingers 65 being provided with interlocking transverse projections and grooves by which the fingers are adjustably attached to the support, substantially as set forth.

3. In a slant-board, the combination of a 70 transverse support and independent laterally-adjustable fingers, arranged side by side with their upper surfaces flush with the upper surface of said support, the support being provided on its upright rear side and the fingers 75 on their upright front ends with interlocking projections and grooves, substantially as set forth.

4. In a slant-board, the combination of a 80 transverse support provided on its upright rear side with a transverse projection, and fingers projecting rearwardly from said support and each provided at its attaching end with a clip which has in its upright front face a transverse groove interlocking with said 85 transverse projection, substantially as set forth.

5. In a slant-board, the combination of a support provided with a transverse guide-groove having a notch in one of its walls, and 90 a finger having a lug which fits in said groove and is adapted to be passed through said notch into said groove, substantially as set forth.

6. In a slant-board, the combination of a 95 support provided with a dovetail groove having a notch in its upper wall, and a finger provided with a dovetail lug which fits in said groove and is adapted to be passed through said notch into said groove, substantially as set forth.

7. In a slant-board, the combination of a 100 support and a finger, both provided with interlocking projections and grooves, and a tension-spring attached to said finger, substantially as set forth.

8. In a slant-board, the combination of a 105 support and a finger, both provided with interlocking projections and grooves by which the finger is attached to said support, a spring attached to the finger and arranged on the under side thereof, and a support on which said spring bears, substantially as set forth.

9. In a slant-board, the combination of a 110 support and a finger provided at its base with an attaching-clip, interlocking projections and grooves formed on the support and clip, a spring secured to said clip and projecting therefrom underneath the finger, and a support upon which the free end of the spring bears, substantially as set forth.

10. In a slant-board, the combination of a 115 main finger, a stub-finger of less length arranged on one side of the main finger, and means by which the stub-finger is attached to the main finger, substantially as set forth.

11. In a slant-board, the combination of a 120 main finger, a support to which said finger is attached, a stub-finger of less length than

the main finger and arranged on one side thereof, and a transverse member connecting the stub-finger with the main finger, substantially as set forth.

5 12. In a slant-board, the combination of a main finger, a support to which said finger is attached, an auxiliary finger arranged on one side of the main finger, and a support con-

necting the auxiliary finger to the main finger, substantially as set forth. 10

Witness my hand this 21st day of June, 1902.

GEORGE R. WILLIAMS.
